Primary Examiner — Elizabeth A. Albert(74) *Attorney, Agent, or Firm* — Andrew F. Young, Esq.;
Nolte Lackenbach Siegel(57) **CLAIM**

The ornamental design for a pen, as shown and described.

DESCRIPTION

FIG. 1 is a perspective view of a pen showing my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is an enlarged cross-sectional view thereof taken along line 8-8 in FIG. 4.

1 Claim, 5 Drawing Sheets(56)
